REVOKING AND RESETTING MECHANISM
FOR WEFT REPLENISHING LOOMS

Clarence R. Kronoff, Worcester, and Alexander C. Krukonis, Auburn, Mass., assignors to Crompton & Knowles Loom Works, Worcester, Mass., a corporation of Massachusetts

Application May 25, 1950, Serial No. 164,171

13 Claims. (Cl. 139—231)

1

This invention relates to improvements more particularly in the multicolor type of weft replenishing loom and it is the general object of the invention to separate the bobbin transfer revoking function from the magazine resetting function so that the revoking function may be performed positively without interference by the resetting function.

Multicolor weft replenishing looms of the kind employing a stationary magazine having several stacks of reserve bobbins ordinarily employ some form of shuttle position detector which is moved to detecting position when the magazine is set for bobbin transfer. If the shuttle is correctly placed for bobbin transfer it moves forwardly with the lay without touching the detector arm and transfer proceeds in usual manner. As the lay approaches front center position it engages the shuttle detector to return it to normal position to reset the magazine for its next operation. The mechanism which sets the magazine for transfer includes a top or setting shaft operatively connected not only to the shuttle detector but also to the latch of the bobbin transerrer arm. When this shaft is rocked back to its normal position by the shuttle detector at front center the transerrer latch is still engaged with the transfer bunter on the lay. It is because of the resetting by the lay that the latch cannot be positively connected to either the shuttle detector or the setting shaft.

If the shuttle is not properly placed when a replenishing operation is called it will engage the shuttle position detector and return it and the setting shaft to their normal positions. Under these conditions the transerrer latch is free to fall out of the path of the lay bunter, but if the latch should be sluggish in its movement and not drop out of the path in time a replenishing operation will occur, in which event the shuttle or bobbin may be damaged. Attempts have been made in the past to effect a positive motion of the transerrer latch when transfer is revoked, but they have generally failed because of the fact that the setting shaft of the magazine has been returned to normal position while the latch is still engaged by the lay bunter, and a positive connection between the shaft and latch could not be used.

It is an important object of the present invention to provide a control for the transerrer latch which will permit it to be moved positively out of the path of the lay bunter by the shuttle detector when the latter is engaged by a misplaced shuttle and thereafter effect resetting of the

magazine at a time in the loom cycle after the lay bunter has moved away from the transerrer latch. This is preferably done by causing the shuttle position detector to perform the revoking function only and assign the resetting function to another mechanism which is not dependent upon the lay to reset the magazine.

Looms of the type already described ordinarily employ a color slide movable angularly first to raise a bobbin releaser without movement of the aforesaid setting shaft and subsequently depress the releaser to effect rocking of the shaft from normal to transfer or setting position. The color slide dwells without angular movement for an interval between its releaser lifting and depressing operations. The angular motions of the color slide and its dwell are derived from a cam operating on a two-pick cycle having a decline to give the color slide a releaser lifting motion separated by a dwell from an incline to give the color slide a releaser depressing motion.

It is another object of the present invention to provide the cam with a tappet or cam surface which acts while the cam dwell controls the color slide to move a resetting member to return the setting shaft to its normal or reset position prior to the time in the loom cycle when the color slide is given its next bobbin releaser depressing movement, a movement which could reset the magazine for another transfer operation. The resetting member may be a vertical rod connected to a cam lever and preferably is not connected directly to the setting shaft but is operative when moving in one direction, such as downwardly, to return the shaft to its normal position.

In the mechanism forming the subject matter of this invention the shuttle detector will remain in its detecting position for a longer period of time than has been common in the past, but the tappet of the cam will effect resetting of the magazine and therefore lifting of the shuttle detector and lowering of the transerrer latch early enough in the forward beat of the lay next succeeding a weft replenishing operation to prevent the latch from being engaged by the lay bunter a second time.

It is another object of the invention to place the setting shaft, shuttle position detector and transerrer latch in a positively connected train all parts of which move in unison, and impress a resetting force on the train by mechanism independent of the lay but acting prior to the time in the cycle of loom operations when the magazine can be set for another replenishing operation.

In order that the invention may be clearly understood reference is made to the accompanying drawings which illustrate by way of example two embodiments of the invention and in which:

Fig. 1 is a vertical section of a loom transverse of the lay looking toward the magazine end of the loom and having the preferred form of the invention applied thereto.

Fig. 2 is a detail front elevation looking in the direction of arrow 2, Fig. 1.

Fig. 3 is an enlarged detail plan view looking in the direction of arrow 3, Fig. 1.

Fig. 4 is a vertical section on line 4—4, Fig. 3.

Fig. 5 is a detail plan view of part of the lay showing the slot therein for the shuttle position detector,

Fig. 6 is a horizontal section on line 6—6, Fig. 1.

Figs. 7, 8 and 9 are diagrammatic views showing various operations of the preferred form of the invention, and

Fig. 10 is a view similar to Fig. 2 but showing a modified form of the invention.

Referring particularly to Fig. 1, the loom frame 1 supports a multi-stack reserve bobbin magazine M which in the present instance has four bobbin releasers indicated front to back at 2, 3, 4 and 5 which are normally down. These bobbin releasers control bobbin releasing cradles a part of which is indicated at 6. Each releaser has pivoted to the upper end thereof a dog 7 and has projecting therefrom top and bottom lugs 8 and 9, respectively.

A color slide 10 is mounted for horizontal motion on the magazine under control of a placing lever 11 attached by connector 12 to some part moving in time with the shifting shuttle boxes (not shown) at the opposite end of the loom. The color slide has front and back fingers 13 and 14 so spaced with respect to the releasers that one or the other of the fingers will register with one and one only of the releasers when the color slide is in any one of the four different horizontal operating positions which it can assume.

Extending across the top of the magazine is a setting shaft 15 having secured thereto an elongated horizontal shelf 16 or the like for cooperation with the dogs 7. Secured to the forward end of shaft 15 is an arm 17 cooperating with a locking lever 18 pivoted on the magazine frame at 19. A compression spring 20 is interposed between the arm 17 and lever 18 and normally is in the position shown in Fig. 2 to hold the shelf 16 in its raised normal position. A stop screw 21 is provided for limiting rocking motion of the lever 18.

The color slide 10 in addition to its longitudinal sliding motion also has a rocking motion caused by a rod 25 attached at its upper end to a rocking means 26 operatively related to the color slide and connected at its lower end to an actuator lever 27 floating on the upper end of a rod 28 which is guided at 29. A pin 30 is permanently over the top of the right end of lever 27 and a second pin 31, indicated in dotted lines in Fig. 2, is controlled by the weft detector (not shown) and is normally clear of the lever 27, but when the weft detector initiates the weft replenishing operation the pin 31 will be under the lever 27.

The lower end of rod 28 is connected to a lever 35 rocking about a fixed stud 36 on a stationary stand 37 secured to the loom frame. The rear part of lever 35 has a roll 38 located in groove 39 of a cam C which is secured to the bottom shaft 40 of the loom. This shaft carries a gear 75

41 meshing with another gear 42 of half its size secured to the top lay driving shaft 43. The bottom shaft is on two pick time and cam C rotates once every second picks of the loom. Cam C has a low surface or point 45, a high surface or point 46, and a concentric dwell 47 between the surfaces 45 and 46.

The rear end of shaft 15 has secured thereto an arm 50 attached to the upper end of a depending rod 51 the lower end of which is attached as at 52 to a shuttle position detector holder 53, see Fig. 3. This holder rocks on a stud 54 stationary with respect to the magazine and has a shuttle feeler or position detector 55 secured thereto as at 56.

The matter thus far described is of usual construction and operates in usual manner. Normally, all of the bobbin releasers 2—5 will be down and pin 31 will be forward of lever 27. When the shuttle is at the magazine end and is depleted of weft the pin 31 will move under lever 27 and at this time rod 28 is moved down by low surface or point 45 of cam C. The color slide 10 is thereupon rocked in a counter-clockwise direction as viewed in Fig. 2 to engage the top lug 8 of the releaser registered therewith and move this releaser upwardly so that its dog 7 will overhang the shelf 16, as indicated in dotted lines in Fig. 2. This upward motion of the releaser occurs while the shaft 15 remains at rest and the yielding lock comprising arm 17, lever 18 and spring 20 will not be moved.

The shuttle is then picked at the opposite side of the loom and at some time in the loom cycle prior to return of the shuttle the high surface or point 46 of cam C will lift rod 28 and cause lever 27, moving around pin 30 as a center, to rock the color slide in a clockwise direction, Fig. 2, to engage the lower lug 9 of the previously raised releaser to depress the latter. Upon downward motion of this releaser the overhanging dog 7 will engage the shelf 16 and will rock shaft 15 in a clockwise direction, Fig. 2, thereby lowering rod 51 and causing the shuttle feeler or position detector 55 to move downwardly from its normal idle position to its detecting position shown for instance in full lines in Fig. 8. Down motion of the releaser will rock the corresponding cradle and the lowest bobbin in the associated stack will drop to transfer position in the magazine under the transerrer arm 53. From this description it will be seen that the magazine is actually set for a replenishing operation by high surface 46 of cam C.

The matter thus far described is characteristic of the standard four-color weft replenishing loom which has been in common use for a great many years. The shaft 15 when rocked by the overhanging dog 7 moves the yielding lock including spring 20 so that this lock moves to the other side of a line joining shaft 15 and pivot 19 and yieldingly holds the shelf 16 and the shuttle feeler 55 in a position set for transfer. In the past it has been customary to employ some part of the lay L to engage the shuttle feeler 55 to lift the latter to reset the shaft 15 to its normal position as the lay approaches front center on a bobbin changing beat of the loom. This resetting of shaft 15 under prior practice has occurred while the transerrer latch 59 is engaged with the lay carried bunter 60 and it is for this reason that it has not been possible to use a positive connection between the shaft 15 and the latch when resetting has occurred at front center.

In carrying the present invention into effect

provision is made for delaying the resetting of shaft 15 until after the lay bunter 60 in its backward motion immediately following a bobbin transferring operation has become disengaged from the latch 59. When such a time for resetting shaft 15 is employed it is possible to utilize a positive connection between the shuttle feeler 55 and the latch 59.

It will be understood that when a normal weft replenishing operation occurs in multicolor magazines of prior construction the latch has remained engaged with the lay for an interval of time which has continued after resetting of shaft 15, and because of this fact a loose or lost motion connection has been necessary between the shaft and the latch. When the shuttle S is misplaced under these former conditions it has lifted shuttle feeler 55 and an attempt has been made to lower the latch 59 as shaft 15 is reset, but because of the lost motion connection the latch has frequently failed to drop fast enough to clear the bunter 60 and as a result a bobbin changing operation has occurred while the shuttle is misplaced.

The cam C is provided with a cam face or tappet 70 for periodic two-pick engagement with a lever 11 held by a set screw 72 on a shaft 73 rockable in stand 37. Secured to shaft 73 is a second arm 74 attached to an upwardly extending rod 75 having a slot 76 in the upper end thereof receiving a stud 77 secured to an arm 78 extending rearwardly from the shuttle feeler holder 53, see Figs. 1, 3 and 4. A second arm 80 secured to shaft 73 carries a stop screw 81 overhanging a part of the loom frame to limit clockwise motion of arms 71, 74 and 80 under action of a tension spring 82 connected to a rod 83 extending upwardly from the forward end of arm 80, see Fig. 1.

Arm 71 has a shoe 85 which is held spaced from the cam C by the stop screw 81 for the greater part of the rotation thereof, but as the cam rotates in the direction of arrow α , Fig. 1, tappet 70 will engage shoe 85 to lower rod 75 and lift rod 83 at a time in the loom cycle when the dwell 47 of cam C is in control of the color slide and is holding the latter against angular motion. It is to be understood that shoe 85 is depressed every second pick of the loom at a time before lever 11 can rock to change the horizontal position of the color slide and after the lay has moved rearwardly far enough from front center immediately following a bobbin changing operation to become disengaged from latch 59. It is at this time that rod 75 descends.

Two means are shown herein for connecting the shuttle feeler 55 positively to the latch 59. In the preferred form a shielded flexible wire is used as indicated in Fig. 1. This wire 90 is supported on the loom frame by several clips 91 and has a core 92 which is directly connected as at 93 to a part of the latch 59 forward of its pivotal connection 94 with the transerrer arm 58. The rear end of the core is connected to the stud 77 as at 95, see Fig. 4. By reason of this connection any movement of the shuttle feeler 55 will be immediately and positively communicated to the latch 59.

In operation, setting of the magazine for a bobbin transfer by down motion of a releaser will result in lowering of the shuttle feeler from the position shown in Fig. 1 to the position shown in Fig. 8 at a time in the loom cycle when the lay is still a considerable distance behind front center, this time occurring after the interval during

which lever 11 can rock to move the color slide endwise. This lowering of the shuttle feeler acts through core 92 to lift the transerrer latch 59 into the path of the bunter 60. If the transfer operation is normal the bunter will engage the latch as the lay advances and will cause a counter-clockwise rocking of the transerrer arm 58 to move the selected bobbin from the magazine into the shuttle and this operation will be completed when the lay reaches front center, or its extreme right hand position as viewed in Fig. 1. The lay is provided with a slot 96 cut in the box back 97 to permit the shuttle feeler 55 to remain in its down position throughout the complete forward motion of the lay, and without engagement with the lay at any time. In this respect the shuttle feeler and lay are different from prior constructions wherein the shuttle feeler would be lifted as the lay approaches front center.

The latch will remain engaged with the lay for the remainder of the aforesaid interval during the first part of the rearward motion of the lay, but eventually the bunter will move away from the latch and thereafter tappet 70 will depress shoe 85 to cause a downward motion of rod 75 the effect of which is to cause movement of the shuttle detector and latch from the full line to the dotted line position, Fig. 9, by reason of engagement of the top of rod 75 with stud 77. The top shaft will therefore be reset at some time after disengagement of bunter 60 from latch 59. As the shuttle feeler returns to its normal position the forward end, at the right of Fig. 1, of core 92 will rise to lower the latch 59 to normal position. It will be understood that the flexible wire 90 can swing forwardly with the latch during a normal transferring operation.

If the shuttle is not properly placed for transfer, as suggested in Fig. 7, but projects under the shuttle feeler as the lay beats up it will lift the shuttle feeler 55 from the full line position, Fig. 7, to the dotted line position and in doing so will push down on the flexible wire core 92, thereby positively exerting an upward force on that part of the latch 59 in front of its pivot 94 to lower the latch below the path of the bunter 60 to the dotted line position, Fig. 7, and a transfer will be prevented. By this arrangement the latch 59 is controlled in a manner different from that which has been possible in the past in that it is acted on by a positive force instead of by springs or gravity as formerly. The resetting function, occurring later in the loom cycle, does not interfere with revocation of a called transfer.

Instead of the flexible wire 90 another form of positive connection may be employed between the shuttle detector and the latch, this connection being somewhat similar to connections previously used but differing in that a positive revoking force can be exerted by shaft 15 on the latch. In this modified form shown in Fig. 10 an arm 100 extending from the forward end of shaft 15 is connected to a depending rod 101 the lower end of which is pivoted to the forward end of latch 59 at the connection 93, this rod having positive connection without lost motion with both the shaft 15 and the latch 59.

In the operation of the modified form of the invention the magazine will be reset as already described in connection with the preferred form, but when revocation of a called replenishing operation occurs upward movement of the shuttle feeler 55 will act through rod 51 to rock the shaft 15 back to its normal position and effect

lifting of the rod 101 to exert a positive lifting force on the forward part of the latch 59 to move the latter out of the path of the bunter 60.

The slot 76 at the upper end of rod 75 permits the shuttle feeler 55 to move down to its shuttle detecting position while rod 75 is up and at a time which is normal for setting the detector in the ordinary four-color weft replenishing mechanism. When the detector 55 moves to shuttle detecting position the stud 77 moves to the top of the slot, and as rod 75 descends it returns the detector to normal position. After tappet 70 passes shoe 85 rod 75 rises to the position shown in Fig. 1. This lost motion connection between rod 75 and stud 77 does not prevent prompt movement of the latch 59 by the shuttle feeler 50 in either form of the invention.

The improved resetting and revoking features set forth herein can if desired be used with a pneumatic thread control system including a pneumatic thread remover 105 which is moved downwardly to thread pick-up position when the transerrer arm 58 descends. The remover remains down after the transferring operation and is not returned to its idle non-pick-up position until the lay has its forward motion next following replenishment. This return of the remover may be as set forth for instance in copending application Serial No. 148,423, filed March 8, 1950. The cam tappet 70 operates in correct time for resetting of the magazine as already described and also for resetting the remover to its non-pick-up position.

When pneumatic thread removers such as that indicated at 105 have been used on stationary magazines in the past failure of the magazine to be able to effect revocation of transfer by a misplaced shuttle has resulted in breakage of the remover when the latter has been moved down against the misplaced shuttle by the transerrer arm, but by use of the positive revoking feature described herein likelihood of this breakage is greatly reduced.

From the foregoing it will be seen that the invention sets forth simple means by which the magazine is reset subsequent to a bobbin transferring operation after the bunter 60 has moved away from the latch 59, and because of this fact it is possible to establish a connection between the shuttle detector and the latch such that the latter can be promptly and positively moved out of the path of the lay bunter if a misplaced shuttle engages the shuttle detector. The shuttle position detector can be of the form used heretofore except for the rearwardly extending arm 78, and resetting is effected by the cam tappet 70 which has a fixed relation with respect to the low and high points 45 and 46, respectively, of cam C. This relation effects resetting of the magazine preferably during the time dwell 47 of the cam is in control of the color slide. When a revocation of bobbin transfer occurs a positive force derived from the shuttle feeler is communicated to the transerrer latch 59 either by the flexible wire 90 employed in the preferred form of the invention, or by reason of the rod 101 used in the modified form. It will be understood that in both the preferred and modified forms the slot 76 permits prompt movement of the latch by detector 55. The latch 59 and shuttle detector 55 are parts of a train of positively connected elements which can be moved in unison when a force is applied at any point in the train. In the preferred form core 92 is part of such a train,

while in the modified form arm 101 is in the train.

Having thus described the invention it will be seen that changes and modifications of the foregoing specific disclosure may be made without departing from the spirit and scope of the invention.

What is claimed as new is:

1. In a weft replenishing loom having a lay, a train of positively connected elements all of which move in unison including a setting shaft, a shuttle position detector, and a transerrer latch, the detector normally being in non-detecting position and the latch being normally out of the path of the lay, cam means turning in a two-pick cycle of the loom, operative connections between the cam and said train moving the latter in one direction on the first pick of said cycle to place the detector in detecting position and place the latch in the path of the lay preparatory to a weft replenishing operation, the shuttle if misplaced moving said train in the opposite direction to move the latch out of the path of the lay, and other operative connections between the cam and said train moving the latter in said opposite direction on the other pick of said cycle to reset said train and return the detector and latch to the normal positions thereof.
2. In a weft replenishing loom having a lay, a train of positively connected elements all of which move in unison including a setting shaft, a shuttle position detector, and a transerrer latch, the detector normally being in non-detecting position and the latch being normally out of the path of the lay, cam means turning during loom operation and having two cam surfaces, means moved by the first of said cam surfaces effective to move said train in one direction to place the detector in the detecting position thereof and place the latch in the path of the lay preparatory to a weft replenishing operation, and other means thereafter operated by the other surface of the cam to move said train in the opposite direction and return said detector and latch to the normal positions thereof.
3. In a weft replenishing loom having a lay, a setting shaft, a shuttle position detector, and a transerrer latch connected together and moving in unison in a train, the detector normally being in non-detecting position and the latch being normally out of the path of the lay, cam means having two cam surfaces, means actuated by one of said surfaces moving said train in one direction to move the detector to the detecting position thereof and move the latch into the path of the lay, said latch remaining in engagement with the lay for a given interval of a pick of the loom during a normal replenishing operation, and means actuated by the other cam surface subsequent to said interval moving said train in the opposite direction and returning the detector and latch to the normal positions thereof.
4. In a loom having a lay and weft replenishing mechanism including a transerrer latch normally out of the path of the lay and a shuttle position detector normally in non-detecting position, a cam having two cam surfaces, means operated by one of the cam surfaces moving the detector from the normal position thereof to the detecting position thereof, positive connections between the detector and latch effective to move the latter into the path of the lay when the detector moves to the detecting position thereof, the detector if moved by a misplaced

shuttle in a direction toward the normal position thereof effecting movement of the latch out of the path of the lay by a force transmitted positively through said connections, the latch remaining in engagement with the lay for a given interval of time if a replenishing operation occurs, and resetting means operated by the other cam surface operating at a time subsequent to said interval to return the shuttle detector to the normal position thereof and exert a force through said positive connections returning the latch to the normal position thereof.

5. The loom set forth in claim 4 wherein said resetting means has a lost motion connection with the shuttle detector enabling the latter to be moved toward the normal position thereof by a misplaced shuttle independently of operation of said resetting means.

6. In a weft replenishing loom having a lay, a train of positively connected elements moving in unison and including a shuttle position detector normally in non-detecting position and a transferrer latch normally out of the path of the lay, said train causing the latch to be moved by the detector when the latter moves, cam means rotating in a two pick cycle, means operatively related to said train operated by said cam means moving the train in one direction to move the detector to the detecting position thereof and move the latch into the path of the lay preparatory to a weft replenishing operation of the loom, the latch remaining engaged with the lay for a given interval of time if the replenishing operation occurs, a misplaced shuttle if engaging the detector moving the train in the opposite direction to move the latch out of the path of the lay by a force transmitted positively through said train, and resetting means operated by the cam means subsequent to said interval moving said train in the opposite direction to return the detector and latch to the normal positions thereof.

7. The combination set forth in claim 6 wherein said train includes a flexible shielded wire operatively connected at one end thereof to the shuttle detector and operatively connected at the other end thereof to the latch.

8. The combination set forth in claim 6 wherein said train includes a shaft rockably mounted on the loom, a rod connecting the shaft to the detector and another rod connecting the shaft to the latch.

9. In a weft replenishing mechanism having a lay and a shaft rotating on two pick time, a transferrer latch normally out of the path of the lay but being in engagement with the lay for a given interval of time during weft replenishing operation of a shuttle, a shuttle position detector normally in non-detecting position, means positively connecting the detector and latch and forming with said detector latch a train all parts of which move in unison, cam means having two cam surfaces secured to said shaft, means operating prior to said interval and actuated by one of said cam surfaces to move said train in one direction to move the detector to detecting position and the latch into the path of the lay, and resetting means actuated by the other cam surface subsequent to said interval moving said train in the opposite direction to return the detector and latch to the normal positions thereof, the shuttle if misplaced moving the detector when the latter is in the detecting position thereof and causing said train to move in said opposite direc-

tion to move the latch out of the path of the lay to prevent a replenishing operation.

10. In a weft replenishing loom having a lay, a train of positively connected elements including a shuttle position detector normally in non-detecting position and a transferrer latch normally out of the path of the lay, said detector and latch moving in unison when the train is moved, cam means turning on two-pick time, a lever operatively connected to said train and moved by said cam means to move the train in one direction to move the detector to the detecting position thereof and move the latch into the path of the lay preparatory to a weft replenishing operation, the latch remaining engaged with the lay for a given interval of time during the replenishing operation, and a second lever operatively connected to said train and moved by said cam means subsequent to said interval to move the train in the opposite direction to return the detector and latch to the normal positions thereof.

11. In a weft replenishing loom operating in a two-pick cycle and having a lay and a bobbin transferrer mechanism normally out of the path of the lay as the latter moves forwardly and having also a shuttle position detector normally in non-detecting position, and wherein the transferrer mechanism moves to transfer position into the path of the lay to be operated by the latter during forward movement thereof and the detector moves to shuttle detecting position in one pick of the cycle preparatory to a replenishing operation, means causing the transferrer mechanism and detector to move positively in unison toward transfer position and back to normal position, the detector if engaged by a misplaced shuttle as the lay advances moving the transferrer mechanism positively out of the path of the lay to prevent a replenishing operation, the transferrer mechanism being engaged with the lay incident to a replenishing operation until the lay reaches a given point during the backward motion thereof after weft replenishment, and means effective during the second pick only of said cycle after the lay has reached said point to return the transferrer mechanism and detector to normal position.

12. In a weft replenishing loom operating in two-pick cycles and having a lay and a bobbin transferrer mechanism normally out of the path of the lay as the latter moves forwardly and having also a shuttle position detector normally in non-detecting position, and wherein the transferrer mechanism moves to transfer position into the path of the lay to be operated by the latter during forward movement thereof and the detector moves to shuttle detecting position in one pick of a two-pick cycle preparatory to a replenishing operation, means causing the transferrer mechanism and detector to move positively in unison toward transfer position and back to normal position, the detector if engaged by a misplaced shuttle as the lay advances moving the transferrer mechanism positively out of the path of the lay, the lay being engaged with the transferrer mechanism when a replenishing operation occurs until the lay during the backward motion thereof after weft replenishment reaches a given point, and resetting mechanism having a resetting movement during the second pick only of each two-pick cycle and effective during the second pick of said cycle after the lay has reached said point to return the transferrer mechanism and detector to normal position.

13. In a weft replenishing loom operating in

a two-pick cycle and having a lay and a bobbin transerrer mechanism normally out of the path of the lay as the latter moves forwardly and having also a shuttle position detector normally in non-detecting position, the loom being capable of having a setting operation preparatory to replenishment of a shuttle during the first pick only of a two-pick cycle by movement of the transerrer mechanism from the normal position thereof to transfer position thereof into the path of the lay and by movement of the detector from the normal position thereof to detecting position, positively acting connections between said transerrer mechanism and detector causing the transerrer mechanism to be moved positively out of the path of the lay when the detector is moved away from the detecting position thereof by a misplaced shuttle as the lay moves forwardly, the transerrer mechanism if engaged by the lay during forward movement thereof incident to a replenishing operation remaining engaged with the lay until the latter during the rearward movement thereof after the replenishing operation

reaches a given point, and means operating during the second pick only of the two-pick cycle to effect a resetting operation by return of the transerrer mechanism and detector to the normal positions thereof after the lay has reached said point in said rearward movement thereof, to the end that a resetting operation in the second pick of a two-pick cycle cannot interfere with a setting operation of the loom for a replenishing operation in the first pick of the next two-pick cycle.
